UNITED STATES PATENT OFFICE

CLIFFORD T. RAULE, OF BROOKLINE, PENNSYLVANIA

PROTECTOR FOR BEARING FOR HIGH SPEED SPINDLES

Application filed May 3, 1926. Serial No. 106,376.

My invention relates to the protection of high speed bearings of grinding mechanism and the like from abrasive dust or fine chips.

A purpose of my invention is to automatically apply an outwardly directed blast of air close to the bearing to shield it from water, dust or other foreign matter.

A further purpose is to mount an annularly cupped disk upon a high speed spindle adjacent the spindle bearing, perforating the disk near its circumference to adapt it to maintain a blast of air diagonally outward across the end of the bearing.

Further purposes will appear in the specification and in the claims.

I have preferred to illustrate my invention by one main form only with two minor modifications selecting for the illustration a form which is practical, efficient and inexpensive and which at the same time well illustrates the principles involved.

Figure 1 is a fragmentary side elevation partly broken away in section showing the preferred form of my invention.

Figure 2 is a front elevation of the guard shown in Figure 1.

Figure 3 is a section of Figure 2 taken upon line 3—3.

Figure 4 is a side elevation of the structure seen in Figure 3.

Figures 5 and 6 are front elevations of modified forms.

In the drawing similar numerals indicate like parts.

The danger from foreign matter entering the bearings of rotating tools, present in all cases where fine chips and dust are thrown, is much more marked and serious with grinding machines than with most other types of machine because of the fineness and quantity of the dust thrown and its abrasive action upon the bearings when it does enter them. For this reason I have illustrated my invention as applied to an internal grinder though I recognize its applicability to other rotating tools also.

In Figure 1, I have shown a bearing support 6 within which is mounted a hollow bearing 7 held in place by an externally threaded sleeve 8. Suitable oil holes shown at 9 and

the shaft 10 complete the illustration of what is intended to be typical of any bearing needing protection from dust, dirt, chips or other foreign matter. The shaft is rotated by any suitable pulley and belt or other means not shown.

At its outer end the shaft 10 is shown supporting a chuck 11, whose jaws 12 hold an internal grinder 13.

As is well known these abrasive tools in normal operation of grinding and successive truing up throw off abrasive dust which may hang for a time suspended in the air, to gradually settle into unprotected bearings as well as to the floor.

I protect the bearings by an annular cup guard 14 which is fastened to the shaft at the end of the bearing so as to rotate with the shaft.

In the preferred form the annular cup is apertured as at 15 radially beyond the bearing in such a direction that rotation of the shaft causes flow of air through the apertures from the side toward the grinding tool to the side toward the bearing.

This can be accomplished in a variety of ways, of which I have illustrated one by centrifugal action, one by catching or scooping the air to force it through and one by a combination of centrifugal and scooping action.

In Figures 1-4 I have shown centrifugal action and for this reason have sloped the circumferentially spaced openings 15 outwardly at the same time that they slope toward the bearing side of the guard with the result and effect of causing a strong flow of air through the openings in a diagonal direction toward the bearing and outwardly to cut off and drive away any dust in the air adjacent to the bearing.

In the form shown in Figure 5 the openings 15' are circumferentially diagonal but need not be outwardly directed.

The guard revolves in the direction of the arrow and the forward edges of the openings catch the air and cause it to be driven through the openings toward the bearing.

In Figure 6 I illustrate that the centrifugal and the scooping forms may be combined, the openings scooping the air into the pas-

sages through the guard leading diagonally outward.

For simplicity I mount the guard upon the shaft by means of an integral collar 18 upon the interior of the guard and form an annular space for the air to be fed between it and the outer flange or shell 19 which is also integral with the guard.

In view of my invention and disclosure variations and modifications to meet individual whim or particular need to obtain part or all of the benefit of my invention without copying the structure of the drawing will doubtless become evident to others skilled in the art and I therefore claim all such in so far as they fall within the reasonable spirit and scope of my invention.

Having thus described my invention what I claim as new and desire to secure by Letters Patent is:—

1. In a guard for a shaft-bearing, an annular cup having diagonally outward perforations near its outer circumference, mounted on the shaft adjacent the bearing and facing away therefrom.
2. In a guard for the bearing of a high-speed shaft, an annular cup mounted on the shaft adjacent the bearing, facing away from the bearing and having diagonally outward perforations directed diagonally past the end of the bearing.
3. In a guard for a shaft bearing, an annular cup rotatable with the movable part of the bearing, located close to the fixed part of the bearings and having a diagonally outwardly extending opening directed across the annular opening into the space between the cup and fixed part of the bearing and adapted to cause air to flow from beyond the cup across the said space when the cup is rotated.
